UNITED STATES PATENT OFFICE.

EDWARD E. TAFT, OF MOUNT PLEASANT, IOWA, ASSIGNOR TO THE TAFT MANUFACTURING COMPANY, OF MOUNT PLEASANT, IOWA.

PIPE-HANGER.

No. 928,711.

Specification of Letters Patent. Patented July 20, 1909.

Application filed November 24, 1908. Serial No. 464,282.

To all whom it may concern:

Be it known that I, EDWARD E. TAFT, a citizen of the United States, residing at Mount Pleasant, in the county of Henry and State of Iowa, have invented a new and useful Pipe-Hanger, of which the following is a specification.

The invention relates to improvements in pipe hangers.

10 The object of the present invention is to improve the construction of pipe hangers, and to provide a simple, inexpensive and efficient one, adapted to be readily applied to a rain spout, a down spout, or any other pipe, 15 and capable of off-setting the same from the adjacent wall to prevent dampness and the consequent rusting of the pipe, whereby the life or durability of the rain spout will be materially increased.

20 A further object of the invention is to provide a pipe hanger of this character, capable of enabling rain spouts to be quickly and securely fastened to a wall, and adapted to permit the same to be readily removed for 25 pairs or other purposes.

With these and other objects in view, the invention consists in the construction and novel combination of parts hereinafter fully described, illustrated in the accompanying 30 drawing, and pointed out in the claims here- to appended; it being understood that various changes in the form, proportion, size and minor details of construction, within the scope of the claims, may be resorted to without departing from the spirit or sacrificing any of the advantages of the invention.

In the drawing:—Figure 1 is a perspective view of a pipe hanger, constructed in accordance with this invention. Fig. 2 is a horizontal sectional view of the same. Fig. 3 is a similar view, illustrating another manner of connecting the ends of the pipe wires.

Like numerals of reference designate corresponding parts in all the figures of the drawing.

45 The pipe hanger comprises in its construction an arched bracket 1, designed to be constructed of galvanized sheet metal, or other suitable material and consisting of a single 50 piece of material bent to form two angle sides 2 and a pipe-receiving connecting portion 3, which is spaced from the adjacent wall 4 by the sides 2. The bracket is arranged horizontally, and the sides have outer attaching 55 portions 5 and inner intermediate angularly

disposed converging portions 6. The outer attaching portions are preferably of a size to extend over a plurality of bricks to enable nails 7, or other fastening devices, which pierce the attaching portions to be embed- 60 ded in the mortar between the rows of bricks. By securing the bracket at a plurality of points, a rain spout 8 may be securely fastened to the wall.

The rain spout, which may be constructed 65 of corrugated, or other sheet metal, is fitted against the transverse connecting portion 3, as clearly illustrated in Fig. 2 of the drawing, and it is secured to the same by one or more binding wires 9, passing through alined per- 70 forations 10 of the sides 2 and encircling the pipe. The spout is off-set by the bracket from the wall and an open space is located back of the rain spout for the passage of water, and also to enable the air to readily dry up any 75 moisture at the back of the spout. This will prevent rusting and will greatly increase the durability of the rain spout. The perforations 10 are located near the transverse connecting portion 3, and one of the terminals 80 of the wire is provided with an eye 11 to receive the other terminal 12, which is bent back, as clearly shown in Figs. 1 and 2, whereby the ends of the binding wire are securely fastened together. This mode of fas- 85 tening is advantageous as it does not necessitate the use of a pair of pliers, or any other tool for securing the ends of the wire together. The attached ends of the wire are preferably arranged adjacent to one side of 90 the bracket, as they are practically concealed from view. In Fig. 3 of the drawing the terminals 13 of the binding wire 14 are twisted together, a pair of pliers or other tool being employed for connecting the ends of the 95 wires.

Having thus fully described my invention, what I claim as new and desire to secure by Letters Patent, is:—

1. A pipe hanger comprising a bracket 100 consisting of a single piece of sheet metal bowed outwardly at an intermediate point and composed of a straight central projecting portion arranged to receive and off-set a pipe from a wall, outwardly extending terminal attaching portions, and sides extending from the inner ends of the attaching portions to the central projecting portion, and a binding wire passing through the sides of 105 the bracket and extending in rear of the cen- 110

tral projecting portion and arranged to encircle a pipe for securing the same against the said projecting portion.

2. A pipe hanger comprising an arched sheet metal bracket composed of outer attaching portions designed to be secured to a wall, intermediate portions extending outward from the attaching portions and converged toward each other, and a transverse connecting portion off-set from the wall by the converging portions and arranged to receive a pipe, the outer attaching portions being provided with perforations for a fastening device, and

a binding wire piercing the intermediate converging portions of the bracket and extending back of the connecting portion and arranged to encircle and secure the pipe against the said connecting portion. 15

In testimony, that I claim the foregoing as my own, I have hereto affixed my signature 20 in the presence of two witnesses.

EDWARD E. TAFT.
